PAISLEY B. HARWOOD, OF MILWAUKEE, WISCONSIN, ASSIGNEE, BY MESNE ASSIGNMENTS, TO CUTLER-HAMMER, INC., OF MILWAUKEE, WISCONSIN, A CORPORATION OF DELAWARE

CONTROLLER FOR ELECTRIC MOTORS

Application filed March 28, 1927. Serial No. 179,082.

This invention relates to improvements in controllers for electric motors, and more particularly to control of certain of the operating motors of blast furnace charging equipment.

Blast furnace tops as ordinarily constructed comprise a pair of charging bells arranged one above the other, and which are so operated as to prevent simultaneous opening of both bells. The charging equipment likewise includes one or more skip buckets adapted to intermittently discharge material into the furnace top at a given point in the periphery thereof. In such equipment the skip hoist is interlocked with the furnace top control, and the latter is in turn interlocked with the bell hoist which operates the bells at the top of the furnace, so that each part of this equipment must complete a given cycle of operation before the skip hoist can operate again. Thus if the skip hoist is faster than the rest of the equipment it must be delayed for the reasons aforementioned. This is almost always the case in furnace top control equipment as heretofore constructed; and one object of my invention is to provide for reducing the time required for operation of certain elements of the equipment whereby the skip hoist may be operated continuously and more rapidly, thus saving considerable time throughout the entire furnace charging operation.

Another object is to provide improved furnace top control equipment whereby the time required for completing the furnace charging operation may be materially decreased.

Another and more specific object is to provide means for expediting the material distributing operation, whereby continuous normal operation of the other elements of the charging equipment is permitted.

Other objects and advantages will be pointed out or will be apparent in the course of the following description.

The accompanying drawings illustrate an embodiment of my invention which will now be described, it being understood that various changes may be made in the details of construction and operation of the controller without departing from the spirit and scope

of my invention as set forth in the appended claims.

In the drawings, Figure 1 illustrates schematically and diagrammatically a furnace top controller constructed in accordance with my invention.

Fig. 2 is an across-the-line diagram of the circuits and connections illustrated in Fig. 1, and

Fig. 3 is a diagrammatic view of one type of furnace top in the control of which my invention may be applied.

Referring first to Fig. 1, the reference character M designates generally a reversible motor for effecting rotary movement of a distributing hopper associated with the small bell of the furnace top; said motor having an armature a, series field SF, and shunt field SHF. Thus assuming closure of knife switches KS and KS¹, motor M is adapted to be connected to lines L¹, L² upon closure of main switch M¹ and simultaneous closure of switches F¹, F², or B¹, B² in the manner hereinafter described. Motor M is connected through suitable gearing to said distributing hopper to effect intermittent partial rotation of the latter in the manner hereinafter described.

Completion and interruption of the energizing circuit of motor M is subject to control by the instrumentalities now to be described. As shown, a normally open switch SK¹ is adapted to be closed upon discharging positioning of one of the skip buckets of a two-bucket hoist, whereas a normally open switch SK² is likewise adapted to be closed upon discharging positioning of the other skip bucket. Control of said switches may be effected in any suitable or well known manner, as by means of nut 5 which is movable by screw 6 connected through any suitable gearing 7 with the skip operating cable or the like.

Switches SK¹ and SK² in turn control the energizing circuit of the operating winding MS of a ratcheting device for effecting step-by-step movement of a "master" switch shown at the lower left hand side of Fig. 1, said circuit being additionally subjected to control by an electromagnetically operable

switch LS. Switch LS is adapted to be held in closed position by means of a mechanical latching device 8, but subject to release upon energization of a tripping coil TC. As shown switch LS is provided with normally open main contacts LS¹, LS² and normally closed auxiliary contacts LS³, LS⁴.

The ratcheting mechanism MS of the master switch is provided with normally closed contacts MS¹ and normally open contacts MS².

The control system further includes a ratcheting device having a winding PS adapted upon energization to effect step-by-step movement of a rotary "position" switch shown at the lower right hand side of Fig. 1. A relay TR having contacts TR¹ is adapted under conditions hereinafter described to complete the energizing circuits of main switch M¹ and switches F¹, F² or B¹, B², selectively. Closure of said contacts TR¹ is subjected to a delay by means of a dashpot TR².

FH and BH indicate rotary switches of a well known type adapted to be connected through suitable gearing with the rotatable distributing hopper; each of said switches being adapted to make one complete revolution upon each rotary movement of the hopper through an angle of 60°.

As shown the master switch is provided with sixty equally spaced buttons, with each alternate one of which a bridging contactor 55 is adapted to make electrical contact for purposes hereinafter described. In other words the bridging contactor 55 is adapted to move through the space of two buttons upon each operation of the master switch ratcheting mechanism. Hence it is obvious that each of the alternate non-active contacts of the master switch might be omitted if desired.

The position switch is provided with forty-five equally spaced active contacts, and the bridging contactor 75 is adapted to be moved through one space upon each operation of the ratcheting mechanism PS of the position switch. The arrangement and functions of the various contact segments on the master and position switches will be described more fully in connection with Fig. 2; it being noted, however, that said switches are preferably provided with suitable legends or marking to indicate the progress of a given furnace charging cycle.

In Fig. 3 I have illustrated diagrammatically a furnace top A having bells B and C, said bells being adapted to be opened and reclosed individually in a predetermined sequence by any suitable means, as indicated at D and E. The distributing hopper F associated with small bell B is likewise adapted to be rotated in one direction or the other through operation of reversible motor M in variable stages under certain conditions hereinafter described. Thus the controller in the

specific form shown herein is adapted to permit reception and discharge of five skip bucket loads by bell B and hopper F without rotation of the latter. After discharge of each of the next five skip loads into hopper F the latter is rotated through an angle of 60° prior to opening or lowering of bell B. In a like manner hopper F is rotated through an angle of 120° prior to discharge of each of the next five skip loads from small bell B. Upon reception of the next skip load by hopper F the latter is rotated in a reverse direction through an angle of 180°, and the next four skip loads are handled in a like manner. Thereafter for the next five skip loads hopper F is rotated in said reverse direction through an angle of 120°, and thereafter for the next five skip loads hopper F is rotated in said reverse direction through an angle of 60°. As will be obvious the provision of means for effecting reverse operation of hopper F will effect a saving of forty per cent of the time required for the furnace charging operation; which is a feature of great importance in this art.

Operation of the device will now be described with more particular reference to the diagram of Fig. 2. With the knife switches KS and KS¹ closed and with the master switch and the position switch in zero position as shown in Fig. 2, upon movement of one of the skip buckets G to the top of the furnace, closure of switch contacts SK¹ is effected in a well known manner. This completes an energizing circuit for the winding MS of the master switch ratcheting mechanism, which circuit may be traced from line L¹ by conductor 50 through the normally closed contacts MS¹ of said mechanism, conductor 51 through said winding, conductor 52, normally closed contacts LS⁴ of switch LS, conductor 53, contacts SK¹, and conductor 54 to line L². The ratcheting mechanism is thus operated to effect movement of bridging contactor 55 through two spaces whereby it engages button 1 of the 0° position indicating contacts. The 0° position indicating lamp is thus lighted, the circuit thereof extending from line L¹ by conductor 56 through said lamp, conductor 57 to contact segment 58, contactor 55 to said button 1, and conductor 59 to line L².

Operation of said ratcheting mechanism also effects opening of contacts MS¹ to effect inclusion of protective resistance r in the energizing circuit of winding MS. Closure of contacts MS² of said mechanism likewise completes an energizing circuit for the winding of switch LS, said circuit extending from line L¹ by conductors 50 and 60 through said contacts MS², conductors 61 and 62 through said winding LS, conductor 63 through normally closed auxiliary contacts LS³ of said switch, conductors 64 and 53 through contacts SK¹, and conductor 54 to

line L^2 . Switch LS upon closure is held in closed position by means of latch 8, pending release of said latch by tripping coil TC in the manner hereinafter described; it being noted that the energizing circuit of winding LS is interrupted immediately through opening of contacts LS³ of said switch. Similarly upon closure of switch LS the energizing circuit of winding MS is interrupted through 10 opening of normally closed auxiliary contacts LS⁴ of the former.

Contacts LS² and LS¹ of switch LS are likewise closed, and upon movement of the second skip bucket to the furnace top switch 15 contacts SK² are closed, thereby completing an alternative energizing circuit for winding MS; which circuit extends from line L¹ through said winding to conductor 52 as heretofore traced, thence through said contacts 20 LS² by conductor 65 through contacts SK², and conductors 66 and 54 to line L². The ratcheting mechanism thus moves bridging contactor 55 through two more spaces to contact button 2 in the 0° section of the master switch. The 0° position lamp remains lighted. Upon closure of contacts MS² in the manner aforescribed an energizing circuit is completed for tripping coil TC, said circuit extending from line L¹ by conductors 50 25 and 60 through said contacts, conductors 61 and 67 through said coil TC, conductor 68 through contacts LS¹, conductors 69 and 65 through contacts SK², and thence to line L² as previously traced. Upon tripping of the 30 latch switch LS assumes its normal position wherein contacts LS¹, LS² are opened and contacts LS³, LS⁴ closed; so that upon return of the first mentioned skip bucket to the furnace top the operation first described is repeated, which effects movement of bridging 35 contactor 55 into engagement with button 3 in the 0° section of the master switch. Operation of the skip buckets effects intermittent operation of the ratcheting mechanism in the 40 manner aforescribed until five bucket loads have been dumped into the furnace top; whereas during such time the motor M has not been energized.

However, upon arrival and dumping of the 45 sixth bucket load into the furnace top switch SK² is closed to effect completion of the energizing circuit of winding MS, as will be obvious; whereupon bridging contactor 55 is moved two spaces from contact button 5 of the 50 0° section of the master switch into engagement with button 1 of the 60° section. The energizing circuit of the 0° position lamp is thus interrupted; whereas an energizing circuit for the operating winding of timing relay TR is completed. Said circuit may be traced from line L¹, by conductor 70 through said winding TR, conductors 71 and 72 to segment 73 of the master switch, contactor 55 to said contact 1, by conductor 74 to the first 55 contact 1 of the position switch, through

bridging contactor 75 to segment 76, and by conductor 77 to line L². Energization of winding TR effects closure of contacts TR¹ of the relay, after a given time delay occasioned by employment of the dashpot TR² (Fig. 1). Contacts TR¹ when closed provide for completion of the energizing circuits of switches M¹, F¹ and F². The energizing circuit of switch M¹ may be traced from line L¹, by conductor 78 through said contacts TR¹, conductor 79 through said winding to conductor 72 and segment 73, and thence through contactor 55 to line L² as just traced. The energizing circuit for switches F¹, F² may be traced from line L¹ by conductor 78 through contacts TR¹ and conductor 79 in parallel through the windings of said switches to segment 80, and thence through contactor 55 to line L² as previously traced.

Closure of switches M¹, F¹ and F² completes an energizing circuit for motor M to effect operation thereof in one direction, as will be obvious; series relays LR¹, LR², having lockout windings, being adapted to control the starting resistances R¹, R² in a well known manner. Closure of switch F¹ likewise effects closure of its auxiliary contacts F¹¹, thereby completing a circuit for the "run" lamp indicated at the lower left-hand side of Fig. 2, said circuit being obvious. Closure of switch F² effects closure of its auxiliary contacts F¹² whereby upon closure of the switch FH, after one-sixth of a revolution of the hopper F, an energizing circuit is completed for the winding PS of the position switch ratcheting mechanism; said circuit extending from line L¹, by conductor 81 through said winding, conductor 82 through normally closed contacts PS¹ of said ratcheting mechanism, conductor 83 through contacts F¹², conductor 84 through contacts FH, and by conductors 85 and 86 to line L². Upon opening of contacts PS¹ protective resistance r¹ is included in circuit with winding PS, as will be obvious. Upon operation of ratcheting mechanism PS, the bridging contactor 75 of the position switch is moved one space, into engagement with button 2 of the 60° section of the position switch. Upon movement of contactor 75 out of engagement with button 1 of said section in the manner just described the aforescribed energizing circuits of switches M¹, F¹ and F² are interrupted, thereby interrupting the motor circuit connections and releasing brake SB to effect stopping of the motor after rotation of the distributing disk through an angle of 60°. As aforescribed suitable means is provided for discharging the material from the bell B prior to dumping of the next bucket load thereonto.

It will be noted that upon movement of contactor 75 into engagement with said button 2 an energizing circuit is provided for

the 60° indicating lamp; said circuit extending from line L¹ through said lamp, by conductor 87 to segment 88, thence through contactor 75 to segment 76 and by conductor 77 to line L².

Upon arrival of the next skip bucket at the furnace top winding MS is again energized, to effect ratcheting of contactor 55 through two spaces into engagement with button 2 of the 60° section of the master switch. This again completes the energizing circuits of switches M¹, F¹ and F²; which circuits may be traced from line L¹ by conductor 78 to bridging contactor 55 as aforescribed, thence to said button 2, by conductor 89 to button 2 of the 60° section of the position switch, through contactor 75 to segment 76 and thence by conductor 77 to line L². Motor M is therefore again operated, and upon rotation of the distributing hopper through an angle of 60° switch FH is again closed. The resulting energization of winding PS effects ratcheting of contactor 75 through one space to engage button 3 of the 60° section of the position switch. It will be noted that movement of said contactor out of engagement with button 2 of said section effects interruption of the energizing circuits of switches M¹, F¹ and F² and stopping of the motor in the manner aforescribed.

Motor M is intermittently operated in the manner aforescribed to carry each skip bucket load to a point 60° removed from that at which it is received, until five loads have been so received and discharged; whereupon contactor 75 of the position switch is moved one space into engagement with button 1 in the 120° section of said switch. It therefore results that upon the next operation of the master switch ratcheting mechanism MS, the energizing circuits of switches M¹, F¹ and F² are completed and will be maintained pending two complete revolutions of switch FH, whereby the distributing hopper is rotated through an angle of 120° prior to stopping of the motor. The next four skip loads are each likewise carried by the hopper F and bell B to a point 120° removed from the point at which they are received from the skip buckets. In the foregoing manner five loads have been received by and discharged from the hopper in the 0° or stationary position of the latter; five loads have been carried to and discharged at a point 60° removed from the point at which they were received; and five loads have been carried to and discharged at a point 120° from the point at which they were received.

When the fifth load is carried to the 120° position the contactor 75 of the position switch will be moved out of engagement with segment 90 and into engagement with segment 91 and button 1 of the 180° section of the position switch. Moreover, upon arrival and discharge of the next load into hopper

F the master switch ratcheting device is operated in the manner aforescribed to effect movement of contactor 55 out of engagement with segment 80 and into engagement with segment 92 and button 1 of the 180° section of the master switch. This again completes an energizing circuit for relay TR, which upon closure completes an energizing circuit for main switch M¹ in the manner aforescribed. However, under these conditions an energizing circuit will be completed for the windings of switches B¹, B², which results in operation of motor M in a reverse direction. It will be noted that the provision of three buttons in each group in the 180° section of the position switch will necessitate three operations of the ratcheting mechanism PS prior to interruption of the motor circuit connections, and hence the distributing hopper will be required to rotate through an angle of 180° prior to lowering of bell B. While I have shown means for reversing the motor to effect movement of the distributing disk to the 180° position, it will be obvious that by extending the segment 80 to cover the 180° section of the master switch such movement could be effected through operation of the motor in the first mentioned direction.

It will be noted that upon closure of the auxiliary contacts B¹¹ of switch B¹ an alternative energizing circuit is provided for the "run" lamp, said circuit being obvious. Likewise upon closure of the auxiliary contacts B¹² of switch B² the energizing circuit for the winding of ratcheting mechanism PS is preset for completion upon closure of switch BH,—the latter being adapted to close once during each one-sixth revolution of the distributing hopper, as described in connection with switch FH.

An important feature of my invention resides in the fact that the material may be fully distributed without requiring movement of the distributing disk through an angle greater than 180°. Therefore after the fifth load has been carried to the 180° position by the hopper, contactor 75 will have moved into engagement with segment 93 and button 1 in the 240° section of the position switch, and upon arrival of the next skip bucket the master switch ratcheting mechanism will effect movement of contactor 55 into engagement with button 1 in the 240° section of the master switch. The aforescribed reverse circuit connections for motor M are thus completed, and the hopper is rotated in a reverse direction through an angle of 120°, as measured by operation of the limit switch BH through two complete cycles. The load is therefore carried by the hopper to the point to which it would have been carried if the hopper had been rotated in a forward direction through an angle of 240°, whereas the time required for such reverse

operation is only one-half as long. Five skip loads will thus be carried by the hopper in a reverse direction through an angle of 120° to a position corresponding to the 240° position of the hopper if operated in a forward direction.

At the end of this period contactor 75 will be moved into engagement with segment 94 and button 1 in the 300° section of the position switch, and upon discharge of the next skip load into the distributing hopper contactor 55 will be moved into engagement with button 1 in the 300° section of the master switch. The reverse circuit connections for motor M are thus again completed, and the hopper is rotated in a reverse direction through an angle of 60° as measured by one complete rotation of switch BH. The hopper is thus moved to a position corresponding to rotation of the hopper in a forward direction through an angle of 300°, while requiring but one-fifth as much time for the operation. After five skip loads have been carried by the hopper to the 300° point by five operations thereof through an angle of 60° in said reverse direction, contactor 75 will be moved to the initial position shown, wherein it engages contact 1 of the first section on the position switch, so that upon arrival of the next skip bucket at the furnace top contactor 55 will be moved into engagement with button 1 in the 0° section of the master switch. The complete cycle aforescribed will then be repeated to effect continuation of the furnace charging operation.

As aforeindicated the contactor 75 by sequential engagement with segments 88, 90, 91, 93 and 94 of the position switch provides for completion of the energizing circuits of the 60°, 120°, 180°, 240° and 300° lamps, thereby visually indicating the condition or progress of the furnace charging operation.

While I have illustrated a controller adapted to provide for discharge of five loads at each of six different angular positions of the hopper, it will be apparent to those skilled in the art that the invention is equally applicable for a charging cycle including discharge of any desired number of loads at any position or any number of positions.

What I claim as new and desire to secure by Letters Patent is:

1. In combination, a device to be rotatably driven, a reversible motor for driving the same, a plurality of normally open switches to be closed and reopened alternately with respect to each other, means adapted upon closure of said switches a predetermined number of times to effect completion of the circuit of said motor for operation thereof in one direction, said means comprising a switch having a plurality of groups of contacts and a contactor to be alternately engaged with and disengaged from the contacts of the respective groups, and another switch having

a plurality of groups of contacts and a contactor to be alternately engaged with and disengaged from the contacts of said groups respectively, the contacts of said last mentioned groups being of different lengths and the contactor associated therewith being operable in accordance with the degree of rotation of said device whereby said motor is operated automatically for different periods during a given cycle, and means adapted upon a given number of operations of certain of said contactors to provide circuit connections for operation of said motor in the opposite direction.

2. In combination, a rotatable device, a reversible electric driving motor therefor, control means for said motor, said means acting automatically to effect a predetermined number of intermittent operations of said rotatable device in one direction throughout a given range and for thereafter effecting a corresponding number of intermittent operations of said device in the same direction throughout a different range, and associated means operable automatically to selectively effect intermittent operations of said device in the reverse direction throughout different ranges, the range of operation in each instance being not in excess of substantially 180 degrees.

3. In combination, a rotatable device, a reversible electric driving motor therefor, control means for said motor, said means acting automatically to effect a predetermined number of intermittent operations of said rotatable device in one direction throughout a given range and for thereafter effecting a corresponding number of intermittent operations of said device in the same direction throughout a different range, and associated means operable automatically to selectively effect a corresponding number of intermittent operations of said device in the reverse direction throughout each of a number of different ranges, the range of operation in each instance being not in excess of substantially one-half of one complete rotation of said device.

4. In combination, a rotatable device, a reversible electric driving motor therefor, control means for said motor, said means acting automatically to effect a predetermined number of intermittent operations of said rotatable device in one direction throughout a given range and for thereafter effecting a corresponding number of intermittent operations of said device in the same direction throughout a different range, and associated means operable automatically to selectively effect a corresponding number of intermittent operations of said device in the reverse direction throughout each of a number of different ranges, the range of operation in each instance being not in excess of substantially one-half of one complete rotation of

said device, the values of the longer ranges of operation in each direction being multiples of the values of the shortest range of operation in the respective directions.

5. In combination, a rotatable device, a reversible electric driving motor therefor, control means for said motor, said means acting automatically to effect a predetermined number of intermittent operations of said rotatable device in one direction throughout a given range and for thereafter effecting a corresponding number of intermittent operations of said device in the same direction throughout a different range, and associated means operable automatically to selectively effect a corresponding number of intermittent operations of said device in the reverse direction throughout each of a number of different ranges, the range of operation in each instance being not in excess of substantially one-half of one complete rotation of said device, the values of the longer ranges of operation in each direction being multiples of the values of the shortest range of operation in the respective directions and certain of the ranges of operation in the respective directions being of equal values.

6. In a controller, in combination, a reversible electric motor, a pair of circuit controlling elements each to be operated progressively and unidirectionally in a series of steps, one of said elements being adapted upon a predetermined plurality of progressive operations thereof to effect completion of the circuit connections of said motor for operation thereof in one direction, the other of said elements being thereafter adapted upon a predetermined number of progressive operations thereof to effect interruption of the motor circuit connections pending subsequent operation of said first mentioned element, said elements being operable automatically and certain of the same having means adapted upon a predetermined plurality of progressive operations thereof to thereafter successively provide reverse circuit connections for said motor.

7. In a controller, in combination, a reversible electric motor, a pair of separately operable switches, associated means for effecting intermittent progressive operation of one of said switches, said switch being adapted upon a predetermined plurality of progressive operations thereof to complete the circuit connections of said motor for operation thereof in one direction, means operable by said motor to effect progressive operation of the other of said switches to thereby interrupt the motor circuit connections after a predetermined period of operation of said motor, said first mentioned switch being thereafter operable to again complete said first mentioned circuit for the motor, and means associated with said first mentioned switch and adapted upon a predetermined plurality of progressive

operations of the latter to thereafter successively provide circuit connections for operation of said motor in the reverse direction.

8. In a controller for electric motors, in combination electroresponsive switches adapted when closed selectively to provide forward or reverse circuit connections for the motor, means for controlling said electroresponsive switches, said means comprising a pair of normally open limit switches to be closed alternately and a plurality of automatically operable switches associated therewith, said last mentioned switches being operable sequentially and unidirectionally in a step-by-step manner to provide for repeated completion of the motor circuit connections and for interruption thereof after different predetermined periods of operation of the motor and to also control said electroresponsive switches for reversal of the motor circuit connections after a predetermined plurality of intermittent operations of the motor in a forward direction.

9. In a controller, in combination, a reversible motor, electroresponsive switches operable selectively to provide forward and reverse circuit connections for said motor, means for controlling the energizing circuits of said electroresponsive switches, said means comprising a pair of switches each having a plurality of contacts and a contactor movable unidirectionally to engage and disengage said contacts in a step-by-step manner, means adapted upon a predetermined plurality of progressive operations of one of said contactors to complete the energizing circuit of certain of said electroresponsive switches whereby the motor is operated in one direction, means adapted upon operation of the motor for a predetermined number of revolutions in said direction to effect operation of the other of said contactors whereby said energizing circuit is interrupted, said first mentioned and second mentioned contactors being operable sequentially and unidirectionally to alternately complete and interrupt said energizing circuit, and means adapted upon predetermined plurality of progressive operations of said first mentioned contactor to thereafter provide for completion of the energizing circuit of other of said electroresponsive switches whereby circuit connections are provided for successive operation of said motor in the reverse direction.

10. In combination, a device to be rotatably driven, a reversible motor for driving the same, a plurality of normally open limit switches to be closed and reopened alternately means adapted upon closure of said switches a multiplicity of times to effect completion of the circuit of said motor for operation thereof in one direction, said means comprising a switch having a plurality of contacts and a unidirectionally movable contactor to be engaged therewith and disengaged therefrom

progressively in response to operation of said limit switches, another switch having a plurality of contacts and a unidirectionally movable contactor to be engaged therewith and disengaged therefrom progressively in response to the degree of rotation of said device to thereby provide for interruption of the motor circuit connections pending re-closure of one of said limit switches, and means associated with said contactors and adapted upon a predetermined plurality of progressive operations thereof to thereafter successively provide circuit connections for operation of said motor in the reverse direction.

In witness whereof, I have hereunto subscribed my name.

PAISLEY B. HARWOOD.
